SWITCH STRUCTURE

Ralph Penn, Goshen, Ind., assignor to Penn Electric Switch Co., Goshen, Ind., a corporation of Iowa

Application December 16, 1943, Serial No. 514,481

11 Claims. (Cl. 200—6)

1

My present invention relates to a switch structure which is in the form of a relatively small unit and which is so designed as to minimize the possibility of vibration causing the switch to operate at undesirable times.

One object of the invention is to provide a switch structure of unit type which is comparatively simple and inexpensive from a manufacturing standpoint, and can be interchangeably mounted adjacent an actuator.

Another object is to provide a switch structure capable of efficient manufacture in very small sizes with a maximum amount of accuracy in operation, wherein pigtail and pivot connections are eliminated, the switch arm being mounted for swinging movement on a leaf spring.

Another object is to provide an inexpensive assembly for mounting the leaf spring on a base, and a switch arm on the leaf spring with the switch arm being so designed as to substantially balance on opposite sides of the leaf spring, thereby minimizing any tendency for the switch to operate either one way or the other when jarred or subjected to vibration.

A further object is to provide a switch structure particularly adapted for operation on an airplane such as for a reversing motor of a cowl flap control of the kind shown in my copending application, Serial No. 523,839, filed February 25, 1944.

With these and other objects in view, my invention consists in the construction, arrangement and combination of the various parts of my switch structure whereby the objects contemplated are attained, as hereinafter more fully set forth, pointed out in my claims, and illustrated in the accompanying drawings, in which:

Figure 1 is a plan view of a switch structure embodying my invention, the cover thereof being removed.

Figure 2 is a similar view showing a section just below the switch arm and the leaf spring for mounting the switch arm shown in cross section.

Figure 3 is a sectional view on the line 3—3 of Figure 1 with the cover in place on the base and showing the switch in one position.

Figure 4 is a similar sectional view showing the switch in another position.

Figures 5, 6 and 7 are sectional views on the line 5—5, 6—6 and 7—7 respectively of Figure 3.

On the accompanying drawings, I have used the reference character B to indicate a base and C the cover therefor. The elements B and C are preferably made of insulating material, such as Bakelite or the like. The base B has a socket 10

therein and adjacent this socket a pair of similar terminal straps 12 are mounted as by screws 13 extending upwardly through the base and threaded into the straps.

The base is molded to form grooves 14 which snugly receive the terminal straps and the terminal straps are provided with down-turned flanges 15 located in the socket 10. A leaf spring 16 is supported by the flanges 15, the lower end of the leaf spring being between them and the flanges, and spring secured together as by a pair of rivets 17.

The leaf spring thereby extends upwardly from the base. A switch arm A is mounted on the upper end of the spring. The switch arm A comprises a pair of arm members 18 having upstanding flanges 19 adjacent each other. The upper end of the leaf spring 16 is received between the flanges 19 and the switch arm and spring are retained assembled relative to each other by a pair of rivets 20.

Mounted in diagonally opposite grooves 21 of the base B, are terminal straps 22 secured in position by other screws 13. The terminal straps 12 and 22 are split at their ends as indicated at 23, and support stationary contacts 24 and 25. Another pair of terminal straps 26 are received in grooves 21 of the base B as by screws 13, and are likewise split at 23, the split ends having stationary contacts 28 and 29 adjustably threaded therein. The terminal straps 12, 22 and 26 are all provided with U-shaped clip ends 30 in which the circuit controlling wires may be soldered.

The switch arm A carries at its outer ends movable contacts 32 and 34 and inwardly therefrom, auxiliary movable contacts 35 and 36. The contacts 35 and 36 are carried by leaf springs 37 secured as by rivets 38 to the arm sections 18. The springs 37 are under tension, so that their outer ends are engaged with the arms as shown in the left-hand half of Figure 3. The switch arms are provided with enlarged openings 39 to clear the contacts 35 and 36.

The cover C is adapted to be held in place by screws 40 which extend through both the cover and the base and then into a supporting structure as shown in my co-pending application. The base B is provided with a socket 41 in which a return spring 42 is mounted. The return spring tends to rotate the switch arm A in a clockwise direction in Figure 3.

For actuating the switch arm in a counter-clockwise direction, an actuating pin 43 is slideable in an opening 44 of the base, and has a

head 48 for engaging the switch arm when the pin is pushed inwardly. A second head 46 preferably of insulating material is mounted on the pin for engagement by an actuating device of any kind. For stopping counter-clockwise movement of the switch arm, I provide a stop bracket 47 secured as by a screw 48 in a groove 49 of the base B.

Practical operation

In the operation of my switch structure, the switch arm A normally assumes the position shown in Figure 3 due to the bias of the spring 42. When the actuating pin 43 is pushed inwardly, it will engage the switch arm and then start it moving in a counter-clockwise direction as shown in Figure 4. First a circuit will be opened at contacts 25 and 34 as shown in this figure, and then a circuit will be opened across 29 and 36. Next a circuit is closed at 28-35 and finally at 24-32. The two ends of the switch arm thereby operate relay and holding circuits in the manner shown in my copending application.

Upon release of the pin 43, the spring 42 will operate the switch arm in a return direction until it finally assumes the position of Figure 3, thus completing a cycle of operations.

My switch structure is particularly adapted for trouble-free operation where vibration is imparted to the switch, the switch arm A, however, being unaffected by such vibrations. This is due to both ends of the switch arms being equal in weight, mass and shape, and thus balanced so that vibration tending to move the arm bodily in either direction will act equally on both ends and thereby eliminate the possibility of movement being imparted to the switch arm due to such vibration. This is particularly desirable where cowl flap motors are controlled, and it is undesirable to alternately energize and de-energize them due to chattering contacts. Furthermore, direct current of low voltage and high amperage is usually used, and such chattering would quickly destroy the usefulness of the contacts, whereas a switch of the kind I disclose may pass through many operating cycles without appreciable harm being done to the contacts.

The switch structure is so designed that a minimum of materials and assembly labor are required to fabricate it and to properly adjust it after fabrication. After the adjustments are made, seals of wax or the like 37 may be applied to the contacts 24, 25, 28 and 29 as shown in Figure 3. The cover C may be readily removed at any time without disturbing the actuating pin 43 which is carried by the base B and thus the switch is a complete unit so that its operation can be checked when the cover is removed.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a switch structure, a base, a leaf spring upstanding therefrom, a switch arm supported intermediate its ends on said leaf spring, extending substantially parallel to said base and having portions of substantially equal mass and shape on opposite sides of the point of support, a pair of stationary contacts on said base on each side of said leaf spring, movable contacts

on the outer ends of said switch arm for coaction with the outer two of said stationary contacts, auxiliary movable contacts on said switch arms spaced inwardly from said first movable contacts for coaction with the inner two of said stationary contacts, a return spring between said base and said switch arm on one side of said leaf spring, and an actuating pin slidably mounted on said base and engageable with said switch arm on the opposite side of said leaf spring from said return spring.

2. In a switch structure, a base, a leaf spring upstanding therefrom, a switch supported intermediate its ends on said leaf spring, extending substantially parallel to said base and having portions of substantially equal mass and shape on opposite sides of the point of support, a stationary contact on said base on each side of said leaf spring, movable contacts on said switch arm for coaction with said stationary contacts, a return spring between said base and said switch arm on one side of said leaf spring, and an actuating pin slidably mounted in said base and engageable with said switch arm on the opposite side of said leaf spring from said return spring.

3. In a switch structure, a base, a leaf spring upstanding therefrom, a switch arm supported intermediate its ends on said leaf spring, said arm having two portions whose centers of gravity are substantially equally spaced from said point of support, said portions being of substantially the same weight, a stationary contact on said base on each side of said leaf spring, movable contacts on said switch arm for coaction with said stationary contacts, a return spring for said switch arm, and an actuating pin engageable with said switch arm to move it in opposition to said return spring.

4. In a switch structure, a base, a leaf spring upstanding therefrom, a switch arm supported intermediate its ends on said leaf spring and extending substantially parallel to said base, a pair of stationary contacts on said base on opposite sides of said leaf spring, contacts on said switch arm for alternate coaction with said stationary contacts, a return spring for said switch arm, and an actuating element engageable with said switch arm in opposition to said return spring for actuating the switch.

5. In a switch structure, a base, a leaf spring upstanding therefrom, a switch arm supported intermediate its ends on said leaf spring, a stationary contact on said base, a movable contact on said switch arm for coaction with said stationary contact, a return spring for said switch arm on one side of said leaf spring, and an actuating element engageable with said switch arm in opposition to said return spring.

6. A switch structure comprising a base, a pair of brackets secured to said base and having down-turned adjacent portions countersunk in said base, a leaf spring between said down-turned portions, means for securing said portions together with said leaf spring between them, whereby the leaf spring extends upwardly from said base, a switch arm comprising a pair of arm portions having adjacent flanges at their ends, means for securing said flanges together with said leaf spring between them whereby the switch arm is mounted for rocking movement relative to said base, stationary contacts on said base, movable contacts on said switch arm, means urging said switch arm to swing in one direction about its connection to said leaf spring as a pivot, and an actuating pin slidably mounted in said base and

engageable with said switch arm to swing it in the opposite direction.

7. A switch structure comprising a base, a pair of brackets secured to said base and having adjacent portions, a leaf spring secured between said portions, said leaf spring extending away from said base, a switch arm comprising two parts having adjacent portions intermediate the ends of the switch arm, said leaf spring being secured between said last portions for swinging movement of the switch arm with the bending of the spring, a stationary contact on said base, a movable contact on said switch arm, and means to swing said switch arm.

8. A switch structure comprising a base, a pair of brackets secured to said base and having downturned flanges adjacent each other, said base having a socket to receive said down-turned flanges, a leaf spring, means for securing said flanges together with said leaf spring between them whereby the leaf spring extends upwardly from said base, a switch arm, and means for securing said switch arm to said leaf spring for rocking movement relative to said base.

9. In a switch structure, a base, a pair of brackets thereon having downturned flanges counter-sunk in said base, a leaf spring riveted between said flanges and extending upwardly from said base, a switch arm comprising a pair of arm portions having adjacent flanges at their ends extending away from said base, said flanges being riveted together with said leaf spring between them whereby the switch arm is mounted for rocking movement in close proximity to said base, a stationary contact on said base, a movable contact on said switch arm, and actuating means engageable with said switch arm to effect such rocking movement.

10. A switch structure comprising a base, a pair of brackets secured to said base and having downturned adjacent portions countersunk in said base, a leaf spring between said down-turned por-

tions, means for securing said portions together with said leaf spring between them, whereby the leaf spring extends upwardly from said base, a switch arm comprising a pair of arm portions having adjacent flanges at their ends, means for securing said flanges together with said leaf spring between them, whereby the switch arm is mounted for rocking movement relative to said base, terminal straps on said base, stationary contacts mounted therein, said base being grooved to snugly receive said terminal straps, screws upwardly through said base for retaining said straps in assembled position in said grooves, said stationary contacts being threaded in said straps, the straps being slotted to permit frictional engagement of the straps with the screws.

11. In a switch structure, a base, a leaf spring extending upwardly from said base, a switch arm mounted thereon for rocking movement relative to said base, terminal straps on said base, stationary contacts mounted therein, said base being grooved to snugly receive said terminal straps, screws upwardly through said base for retaining said straps in assembled position in said grooves, said stationary contacts being threaded in said straps, the straps being slotted to permit frictional engagement of the straps with the screws, and movable contacts for coaction with said stationary contacts.
